C. D. ELLWOOD

LIFTING JACK

Filed Aug. 20, 1924

Inventor,

Charles D. Ellwood

Barnett & Truman

Attorneys.

UNITED STATES PATENT OFFICE.

CHARLES DAVIDSON ELLWOOD, OF RACINE, WISCONSIN, ASSIGNOR TO WALKER MANUFACTURING COMPANY, OF RACINE, WISCONSIN, A CORPORATION OF WISCONSIN.

LIFTING JACK.

Application filed August 20, 1924. Serial No. 733,131.

To all whom it may concern:

Be it known that I, CHARLES D. ELLWOOD, a citizen of the United States, residing at Racine, in the county of Racine and State of Wisconsin, have invented certain new and useful Improvements in Lifting Jacks, of which the following is a specification.

This invention relates to the class of devices known as lifting jacks, and more particularly to such a device designed to have an exceptionally long lift in proportion to its size and height when in lowered or collapsed position.

While there are numerous uses for such a jack, it is especially adapted for advantageous use with the over-size or balloon tires now used extensively on motor vehicles. For this use it is desirable to have a jack which is compact and of a small vertical height when lowered, in order to be placed under the low axle or other frame parts when the tire is collapsed, and capable of a comparatively long lift to elevate the car above its normal driving height in order that the tire may be changed.

The jack here disclosed is of the type employing a plurality of screw threaded members working one within another and each contributing its share to the total lift of the jack. As here shown, the jack comprises a pair of non-rotary screws, one of which is stationary and the other vertically movable to lift the load. A hollow sleeve surrounds the two screws when the jack is lowered, and has integral nuts formed in its two ends to engage the two screws respectively. Rotary means mounted in a fixed standard engages the outer surface of the sleeve to rotate same, and at the same time allows the sleeve to move vertically upon the stationary screw. A jack of this type is disclosed in the copending application of Irwin E. Dearsley, Serial No. 732,040 filed August 14, 1924. The present application discloses improvements on the form of jack claimed in this copending application.

The particular object of the present invention is to provide a jack of this type, wherein a plurality of driving means for the rotary sleeve are used, so as to provide a balanced structure, which may be centered under the load, and which will tend to counteract the lateral stresses normally

tending to force apart the driving means and the sleeve. A further object is to provide an improved means for holding the inner screw against rotation.

Other objects and advantages of the invention will be readily apparent from the following detailed description of an approved form of the apparatus.

In the accompanying drawing:

Fig. 1 is a side elevation of the jack.

Fig. 2 is a central vertical section on an enlarged scale, taken substantially on the line 2-2 of Fig. 1.

Fig. 3 is a transverse section taken substantially on the line 3-3 of Fig. 1.

The standard 1 comprises a base portion 2, and an upright central hollow sleeve 70 member 3 which is exteriorly threaded throughout substantially its entire height. An inner screw member 4, having a load-supporting cap 5 at its upper end, is freely slidable vertically through the hollow sleeve 75 3. An outer hollow cylindrical sleeve member 6 is formed with a nut 7 in its lower end meshing with the stationary screw 3, and a smaller nut 8 in its upper end meshing with the inner lifting screw 4. When the 80 jack is in lowered or collapsed position the two screws 3 and 4 are nested within the outer sleeve 6.

The outer cylindrical surface of sleeve 6 is provided with a series of longitudinally extending gear teeth 9 which are parallel to the axis of the sleeve and of the screw members nested therein. Mounted in suitable bearings in the oppositely disposed housing extensions 10 at the upper end of the 90 standard 1, are a pair of similar short inclined shafts 11 and 12, to which are secured the driving worms 13 and 14 respectively. These worms 13 and 14 mesh with the teeth 9 of sleeve 6 at diametrically opposite points, and as will be noted in Fig. 3 the worm 14 is threaded oppositely to worm 13, so that when both worms are rotated in the same direction they will cooperate in imparting rotary movement to 100 the sleeve 6. A small spur gear 15 secured to the shaft 12, and a similar gear 16 secured to shaft 11, both mesh with a larger spur gear 17 keyed to a short driving shaft 18 mounted in one side of the standard. A 105 socket 19 secured to the outer upper end of

shaft 18 provides means for attaching any suitable form of removable handle by which the driving gear 17 may be rotated. Anti-friction thrust bearings 20 are provided between the pinions 15 and 16, the worms 13 and 14 and the adjacent bearings for shafts 11 and 12 in the stationary standard.

A bar or rod 21 is suspended by a pivot 10 between ears 23 at one side of the load-supporting cap 5. Bar 21 moves up and down between a pair of fixed ears 24 at one side of standard 1, and serves as a means to prevent rotation of the inner screw 4. If one should desire at any time to rotate 15 the inner screw 4 with relation to the other parts, it is only necessary to remove the rod 21 from between the locking ears 24.

In operation, a continuous rotation of 20 driving gear 17 by means of the removable crank handle, will simultaneously rotate the two worms 13 and 14 at the same speed, and due to the opposite directions of the threads on these worms they will both cooperate to rotate the sleeve 6 in the desired 25 direction. Since the side thrusts of these two worms are toward one another, they tend to balance the stresses in the mechanism and keep the screws properly centered beneath the load. The symmetrical arrangement 30 of the driving means at opposite sides of the standard also balances the weight of the jack. The rotation of sleeve 6 in the proper direction will elevate it along the stationary screw 3. At the same time, 35 the inner screw 4 which is held against rotation by the bar 21 engaging with the stationary standard 1, will be elevated with respect to the upwardly moving sleeve 6 through the engagement of the rotating nut 40 8 in the upper end of the sleeve with the threads on screw 4. A reverse rotation of the operating handle will return the parts to lowered position, with the two screws 45 nested together and within the rotary sleeve 6 and standard 1.

By mounting the worms 13 and 14 on inclined axes, the necessarily inclined worm teeth will be vertically positioned on that side of the worm which meshes with the 50 vertically extending teeth on sleeve 9. Since the directions of the threads on the two worms are reversed, the inner threads of each will have the same inclination, therefore with the two shafts 11 and 12 in the 55 same inclined plane, both worms will mesh properly with the vertical threads of sleeve 9. This inclination of the worms, and the driving connections therefor, will also cause the operating handle to project upwardly at a convenient angle.

The gear reduction provided between the driving gear 17 and the pinions 15 and 16, in addition to the large reduction provided by the worm and worm wheel drive and 60 the screw drive between the standard and

lifting members, permits very heavy loads to be elevated with comparatively little effort.

I claim:

1. A lifting jack comprising a stationary 70 standard and a rotary lifting member having screw-threaded engagement with one another, the lifting member having longitudinally extending gear-teeth on its outer cylindrical surface, and a pair of driving 75 worms mounted on the standard with their axes in the same inclined plane and meshing with the teeth on the lifting member at diametrically opposite points.

2. A lifting jack comprising a stationary 80 standard and a rotary lifting member having screw-threaded engagement with one another, the lifting member having longitudinally extending gear-teeth on its outer cylindrical surface, a pair of driving worms 85 mounted on the standard with their axes in the same inclined plane and meshing with the teeth on the lifting member at diametrically opposite points, and means for simultaneously driving the worms from a dis- 90 tance.

3. A lifting jack comprising a stationary 95 standard and a rotary lifting member having screw-threaded engagement with one another, the lifting member having longitudinally extending gear-teeth in its outer cylindrical surface, and rotary driving 100 means mounted on the standard and engaging the lifting member at diametrically opposite points to rotate the lifting member 100 and at the same time allow it to move vertically.

4. A lifting jack comprising a stationary 105 standard and a rotary lifting member having screw-threaded engagement with one another, the lifting member having longitudinally extending gear-teeth on its outer cylindrical surface, and a pair of similar 110 driving means mounted on the standard at opposite sides of the lifting member and engaging same to rotate it while allowing it to move vertically.

5. A lifting jack comprising a standard 115 having an exteriorly screw-threaded portion, a lifting member interiorly threaded to engage this portion and provided on its outer cylindrical surface with longitudinally extending gear-teeth, and a pair of oppositely threaded driving worms mounted on the 120 standard with their axes in the same inclined plane and meshing with the teeth on the lifting member at diametrically opposite points.

6. A lifting jack comprising a standard 125 having an exteriorly screw-threaded portion, a lifting member interiorly threaded to engage this portion and provide on its outer cylindrical surface with longitudinally extending gear-teeth, a pair of oppositely threaded driving worms mounted on the 130

standard with their axes in the same inclined plane and meshing with the teeth on the lifting member at diametrically opposite points, and means for simultaneously driving the worms from a distance.

7. A lifting jack comprising a standard having a screw-threaded portion, a load-supporting screw freely movable longitudinally through the standard, means for holding the screw against rotation, a hollow sleeve surrounding the screw and standard, and interiorly threaded at opposite ends to engage the screw and standard respectively, and a pair of similar driving means mounted on the standard and engaging the sleeve at diametrically opposite points for rotating the sleeve.

8. A lifting jack comprising a standard having a screw-threaded portion, a load-supporting screw freely movable longitudinally through the standard, means for holding the screw against rotation, a hollow sleeve surrounding the screw and standard, and interiorly threaded at opposite ends to engage the screw and standard respectively, the outer surface of the sleeve being provided with longitudinally extending gear-teeth, and a pair of driving worms mounted on the standard with their axes in the same inclined plane and meshing with the teeth at diametrically opposite points.

9. A lifting jack comprising a standard having a screw-threaded portion, a load-supporting screw freely movable longitudinally through the standard, means for holding the screw against rotation, a hollow sleeve surrounding the screw and standard,

and interiorly threaded at opposite ends to engage the screw and standard respectively, the outer surface of the sleeve being provided with longitudinally extending gear-teeth, a pair of driving worms mounted on the standard with their axes in the same inclined plane and meshing with the teeth at diametrically opposite points, and means for simultaneously rotating the two worms from a distance.

10. A lifting jack comprising a standard having a screw-threaded portion, a load-supporting screw freely movable longitudinally through the standard, means for holding the screw against rotation, a hollow sleeve surrounding the screw and standard, and interiorly threaded at opposite ends to engage the screw and standard respectively, the outer surface of the sleeve being provided with longitudinally extending gear-teeth, a pair of oppositely threaded driving worms mounted on the standard with their axes in the same inclined plane and meshing with the teeth at diametrically opposite points, a short shaft mounted in the standard and having an attaching member for a removable handle, and gear connections between the shaft and the worms.

11. A lifting jack comprising a standard, a lifting screw longitudinally movable through the standard, and a bar pivoted to the upper end of the screw, and removably slideable between a pair of ears at one side of the standard, for holding the screw when desired against rotation while allowing it to move vertically.

CHARLES DAVIDSON ELLWOOD.
